Primary Examiner — Leanne Was-Englehart*Assistant Examiner* — Jasmine L. Comedy(74) *Attorney, Agent, or Firm* — Warner Norcross + Judd
LLP(57) **CLAIM**The ornamental design for a door assembly, as shown and
described.**DESCRIPTION**FIG. 1 is a front perspective view of the door embodying the
new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a front perspective view of the door assembly
partially opened.The figures show features in broken lines that do not form
any part of the claimed design. Further, the broken lines
immediately adjacent the solid line portions of the design
form the boundary of the design, with the broken lines
forming no part of the claimed design.**1 Claim, 7 Drawing Sheets**(56)
